UNITED STATES PATENT OFFICE.

JOHN FRANCIS McCOY, OF NEW ORLEANS, LOUISIANA, ASSIGNOR OF
ONE-EIGHTH TO JOHN A. McCOY, OF NEW ORLEANS, LOUISIANA.

CURB.

No. 802,772.

Specification of Letters Patent.

Patented Oct. 24, 1905.

Application filed June 2, 1904. Serial No. 210,822.

To all whom it may concern:

Be it known that I, JOHN FRANCIS McCoy, a citizen of the United States, and a resident of New Orleans, in the parish of Orleans and 5 State of Louisiana, have invented a new and Improved Curb, of which the following is a full, clear, and exact description.

My invention relates to a curb for sidewalks and streets and to certain accessories 10 thereto.

The objects of my invention are to provide curbs with an indestructible corner-bond to protect the surfaces and edges of the curb and gutter and at the same time to have this 15 bond do duty as a sanitary street-sprinkler. The bond is capable of use in other places than on curbs—as, for example, on street-car rails—and this application comes within the spirit of my invention.

20 Further objects and advantages of the invention will appear in the course of the subjoined description, and the actual scope thereof will be defined by the annexed claims.

Reference is to be had to the accompanying 25 drawings, forming a part of this specification, in which similar characters of reference indicate corresponding parts in all the figures.

Figure 1 is a perspective view of a portion 30 of a street, showing a curb and a street-car rail both provided with a preferred form of my invention. Fig. 2 is a sectional view showing the curb and bond and one means of securing the parts in position. Fig. 3 is an enlarged sectional view similar to Fig. 2, 35 showing a modification. Fig. 4 is a sectional view of the bond, taken on the line 4-4 of Fig. 1. Fig. 5 is a sectional view of the bond in a modified form. Fig. 6 is a sectional view similar to Fig. 5 in a still further modified 40 form. Fig. 7 is a front view of the bond, with parts, in section on the line 7-7 of Fig. 6, indicating the method of securing the parts together. Fig. 8 is a fragmentary view similar to Fig. 7, showing a modification; and Figs. 45 9, 10, and 11 are sectional views of rails with my improvement applied thereto.

In the drawings, *a* represents a curb provided with my improved bond *b*. This bond is preferably made of steel and is composed 50 of two sections, (indicated in Fig. 3 by *b*' and *b*.) Although the shape of these sections is not material and they are shown in several shapes in Figs. 5 and 6, for example, it is essential that there should be a space between

them for the admission of water. In the outside of one of the sections are conical openings *B*' for the distribution of the water forced into the space between the two main sections. When formed of two sections, as shown in Figs. 3 and 5, they are secured together by 55 means of projections and grooves, (indicated at *B*.) The bond, although preferably made in two sections, as indicated in the figures mentioned, may be made of a single piece of metal, as indicated in Figs. 9, 10, and 11. In either 60 case the bond will necessarily be formed in longitudinal sections, and at their ends where they meet they are preferably provided with offset portions *b*', fitting each other.

For securing the bond in the plastic material of the curb various forms of anchors may be employed. One of these (indicated at *c* in Figs. 2 and 6) has a portion *C* surrounding the outside surface of the bond, which is provided with openings *C*', registering with the 65 openings *B*' for an obvious purpose. When this form of bond is employed, it is preferably set into the piece *b*', as clearly shown in Fig. 7, in such a manner as to overlap the projecting ends of the two sections of the bond. The rearwardly-extending portions of the bond may be offset, as shown at *C*', to more 70 securely hold it in position. Another form of anchor is shown in Figs. 3 and 4 at *c*'. These anchors may conveniently be secured 75 to the section *b*' by means of screw-threaded nuts *c*'; and the anchors have offset portions *c*'. 80 85

In Fig. 5 is indicated at *c*' still another modification of the anchors. These are preferably pivoted to the section *b*' at the point *c*' and have offset portions *c*'' on one or more sides. In the form represented in Fig. 5 the rear portions of the section *b*' are provided with corrugations or other irregularities *b*'' for the purpose of more securely holding the bond in the plastic work of the curb. 90 95

d represents a hydrant or other supply for water. It should be connected to the bond at any desired point, and the bond should be provided at various places with sections *e*, provided with stop-cocks for shutting off the water and turning it on. A convenient form of stop-cock for this purpose is represented in Fig. 4. The section *e* is provided with internal screw-threads and with a screw-cock *e*', having a passage *e*'' therein and a projection *e*''' for the convenient attachment of a wrench. 100 105

The operation of this device will be obvious from the construction shown.

Figs. 7 and 8 show overlapping joints b^4 for securing adjacent sections of the curb together.

In Figs. 9, 10, and 11 the car-rails f are shown provided with three different forms of bonds and sanitary sprinklers f^1 , f^2 , and f^3 . The bond or sprinkler f^1 is removable from the rail and is provided with a projection f^2 for securing it in the material of the road-bed. The bond or sprinkler f^2 is also removable from the rail, and it is provided with a slot f^3 for removably securing it to the rail. The bond or sprinkler f^3 is integral with rail. Each one of these bonds or sprinklers is hollow and is provided with conical openings for the discharge of water in streams.

From the various modifications illustrated it will be obvious that my invention is not limited to any particular embodiment of the principle of the invention disclosed, but that it is capable of construction in many different forms.

25 The bond should preferably be made of steel, so as to secure long life and freedom from breakage by any ordinary usage.

As shown in Figs. 1 and 2, the gutter g is intimately connected with the invention, and the water discharged from the sprinkler will readily flow back into the gutter and be discharged therefrom in the ordinary manner.

It will be obvious that this improved bond will add greatly to the durability of the curbs now manufactured in most of our cities and that it will also provide for the sanitary sprinkling of the streets without the use of the costly and primitive sprinkling-carts which

are now employed. The water may be turned on and off very easily and quickly, and it can be so arranged that the water for a whole street or for a whole section of a city may be turned on at once from one hydrant.

Having thus described my invention, I claim as new and desire to secure by Letters Patent—

1. A curb having a longitudinal hollow metallic bond provided with perforations in its face, the face being flush with the surface of the curb.

2. A curb having a metallic bond comprising a curved perforated section, and an angular section, said sections being keyed together in such a manner as to leave a space for water between them.

3. A curb having a hollow bond comprising a curved perforated section and an angular section, means for securing said sections together, and means for securing the bond to the curb.

4. A curb having a hollow metallic bond composed of a series of sections provided with perforations in their faces, and anchors embedded in the curb and removably connected with the bond.

5. A curb having a hollow metallic bond consisting of a series of sections with overlapping ends, means for securing said sections together, and connections from said sections to a water-supply.

In testimony whereof I have signed my name to this specification in the presence of two subscribing witnesses.

JOHN FRANCIS MCCOY.
